UNITED STATES PATENT OFFICE

2,223,449

RIVET SETTING MECHANISM

Louis C. Huck, Grosse Pointe Village, Mich., assignor to Huxon Holding Corporation, a corporation of Michigan

Application May 14, 1935, Serial No. 21,472

10 Claims. (Cl. 60—54.5)

The invention relates to a rivet setting mechanism and it has particular relation to a mechanism for setting rivets of a type including a tubular element and a pin extending therethrough and which is inserted and set from one side of the structure to be riveted.

More particularly the invention constitutes an improvement in rivet setting mechanisms over those disclosed in the copending applications for 10 patent of Louis C. Huck et al., Serial No. 615,544, filed June 2, 1932, now Patent No. 2,053,718, and Louis C. Huck et al., Serial No. 636,480, filed October 6, 1932, now Patent No. 2,053,719.

In the first of the above mentioned copending 15 applications for patent a rivet setting mechanism was set forth which included a rivet setting gun and a fluid pressure boosting device connected thereto by flexible tubing so that the gun might be used at points remote with respect 20 to the booster and without moving the booster each time the gun would be moved. It also was set forth in this application for patent that air pressure would be used in the booster device for building up a liquid fluid pressure which would 25 be supplied to the gun for operating it during the rivet setting procedure. Moreover, this rivet setting mechanism was so designed and constructed that by manipulating a trigger on the gun, operation of the booster device and setting 30 of the rivet could be controlled entirely by the operator manipulating the gun even though the booster device would be located some distance away.

In the last mentioned of the copending applications for patent, a rivet setting gun of somewhat different character is disclosed which also operates in conjunction with a booster device such as set forth in the first mentioned copending application for patent. The gun in the second case includes two pistons one of which operates first when the trigger on the gun is pulled to effect a certain phase of the rivet setting operation and then upon completion of this phase, the second piston automatically becomes operative to cause an auxiliary anvil to move over the head of the tubular part of the rivet to radially contract a portion thereof into grooves in the pin forming a part of the rivet. Upon completion of this operation, the liquid fuel pressure 45 is automatically increased to such extent that the first piston continues its movement to break the pin at a predetermined point.

While the rivet setting mechanisms set forth in these applications for patent have been highly satisfactory, certain improvements have been de-

sirable and form the basis of this invention. These may generally be indicated in the objects of the invention but a more detailed explanation will be found in the description. Objects of the invention additional to those outlined hereafter will be apparent from this description, from the drawings to which it relates and from the claims hereinafter set forth.

One object of this invention is to provide a rivet setting gun which is more efficient in operation and which may more easily be handled and manipulated by the operator. 10

Another object of the invention is to provide an improved jaw mechanism and operating arrangement therefor which will enable using a 15 smaller diameter of barrel on the gun and also facilitate insertion of the jaws during assembly of the gun.

Another object of the invention is to provide an improved rivet setting mechanism including 20 a riveting gun and a fluid pressure boosting device, wherein means are provided for limiting the building up of liquid fluid pressures in the gun and booster even though the operator maintains the trigger on the gun in its rivet setting 25 position after completion of the rivet setting operation.

Another object of the invention is to provide an improved rivet setting mechanism including 30 a rivet setting gun and booster device wherein 35 a reservoir is provided in connection with the liquid fluid side of the system for maintaining the liquid fluid spaces filled with liquid and for replenishing the fluid supply at any time it is needed and particularly for supplying additional 40 liquid fluid in the event any vacuum tends to occur during return of the booster piston in which event air would tend to seep into the liquid fluid side unless liquid fluid were injected to insure prevention of any vacuum spaces. 45

Another object of the invention is to provide an arrangement wherein upon completion of the rivet setting operation or in any event where the liquid fluid becomes subjected to pressure above that necessary to set the rivet, the liquid fuel may flow into the reservoir and prevent building up of an undesirably high fluid pressure. 50

Another object of the invention is to provide an improved valve arrangement in the booster device which is automatically controlled by the 55 trigger or operating element on the gun.

Another object of the invention is to provide a mechanism, and particularly a riveting mechanism, involving the use of fluid pressure responsive means, wherein automatic means is 55

employed for economizing on the fluid required for operating the fluid pressure responsive means.

Another object of the invention is to provide 5 an improved riveting gun or the like employing jaws therein, wherein means are provided for manually opening the jaws.

Another object of the invention is to provide 10 an improved system including a riveting gun and fluid pressure boosting mechanism, wherein liquid fluid under high pressure is used to operate the piston in the pressure boosting device.

For a better understanding of the invention reference may be had to the drawings wherein: 15 Fig. 1 is a side elevational view of a riveting gun and fluid pressure boosting device constructed according to one form of the invention with the boosting device shown partly in cross section for the purpose of illustrating certain 20 details thereof.

Fig. 2 is a cross-sectional view taken substantially along the line 2—2 of Fig. 1 but on an enlarged scale.

Fig. 3 is a cross-sectional view on a slightly 25 smaller scale taken substantially along the line 3—3 of Fig. 2.

Fig. 22 is a cross-sectional view taken substantially along line 22—22 of Fig. 21.

Fig. 23 is a cross-sectional view of a rivet 70 adapted to be set by the riveting mechanism illustrating the rivet as initially inserted through openings in a structure to be riveted.

Fig. 24 is a similar cross-sectional view illustrating the rivet after it has been set.

75 In general the construction shown by Fig. 1

comprises a riveting gun 8 and a pressure boosting device 9. Fluid under pressure, such as air, actuates the booster and the latter supplies liquid under a greater pressure to the gun for operating the latter. Control of the mechanism is effected at the gun by means of a trigger valve in an air line extending from the booster device. The construction of the booster device will be described first.

Referring to Figs. 1 and 2, the booster device 10 9 comprises a cylinder 10 connected at its ends to end walls 11 and 12 respectively. A piston 13 is reciprocatory in the cylinder and at opposite sides the piston is provided with oppositely disposed cup-shaped sealing rings 14 around the 15 outer edge for preventing fluid under pressure from leaking past the piston, and these rings may be retained in place by slightly smaller ring plates 15 secured by bolts to the piston body and which press triangular wedge rings 15' into the 20 cup grooves. A piston rod 16 projects through the piston and is rigidly secured thereto by means of a shoulder 17 on one side of the piston and a nut 18 on the other. This rod projects through an opening in the end wall 12 of the cylinder 25 and is reciprocatory in a small barrel 20 secured by bolts 21 to this end of the cylinder. Along the opening in the wall 12 and in the adjacent end of the barrel, cup-shape sealing rings 22 are provided for preventing fluid under pressure from 30 escaping along the rod 16 and the rings at one side are disposed oppositely to those at the other side to provide a positive seal against fluid escaping from the cylinder and barrel. Between the oppositely disposed sealing rings, a vent 23 is provided so that any air leaking from cylinder 10 past the first rings will be allowed to escape to the outside. The outer end of the barrel is connected to a high pressure hose 24 of flexible character which extends to the riveting gun and 40 it should be understood that the barrel and hose will be filled with liquid fluid such as an oil suitable for this purpose and that when the piston rod 16 moves to the right this oil will be forced into the gun.

45 It may be mentioned at this time that the cylinder and barrel are mounted on a suitable frame 26 which is supported at the barrel end by a caster 27 and at the opposite end by a pair of wheels 28 so that the booster can be readily moved from place to place whenever this is necessary.

The piston 13 is reciprocated by air under pressure and owing to the relatively large diameter of the piston as compared to the diameter of the piston rod and the barrel into which it projects, 55 a very high pressure on the liquid fluid in the barrel and hose 24 will be obtained when a relatively low air pressure is used in the cylinder. For actuating the piston, a valve mechanism 30 is mounted on the left end wall 11 of the cylinder, 60 and this mechanism as best shown by Figs. 2 and 3 has an elongated bore 31 of substantially uniform diameter which terminates in a slightly larger bore 32 at the right end thereof. Within the bore, a reciprocatory valve operating element 65 33 is provided which has piston-like heads indicated at 34, 35 and 36 respectively, which operate in the smaller portion of the bore 31 and closely fit therein to prevent leakage of air therewith. At the right end of the element 33 a pin 37 is 70 provided which projects into the head 36, and this pin terminates at its right end in a head 38 that is reciprocatory in the larger portion 32 of the bore. This head has a projecting portion 39 of smaller diameter and around this projec- 75

tion a piston sealing ring 40 may be provided. The larger portion 32 of the bore is closed at its outer end by a cap 41 which is connected to a conduit 42.

5 At the left end of the bore 31, a piston 43 is provided which is adapted to move the element 33, and this piston similarly to the piston 38 at the right end of the bore terminates in a smaller projection around which a piston seal is provided. Air is introduced to the valve by an air line 44 shown by Fig. 3, communicating with a longitudinal aperture 45 that extends to and communicates with the left end of the bore 31 at the left side of the piston 43 by means of an aperture 46 provided in a cap 47 that closes this end of the bore. Air may enter the bore 31 through an opening 48 adjacent the right side of the head 35 when the reciprocating element 33 is at the left end of the bore. The space between the heads 35 and 36 when the valve element is in the position shown also is in communication with a conduit 49 by means of an opening 50, and this conduit is adapted to introduce and discharge air to and from the right end of the cylinder 10 as will presently be explained.

20 The bore 31 immediately to the left of the head 35 is in communication with the left end of the cylinder by means of an opening 51 extending through the end wall 11, and immediately to the right of heads 34 and 36 openings 52 and 53 in the wall are provided to allow air at the left and right ends of the cylinder to exhaust to atmosphere. With the parts in the position shown, air at the left side of piston 13 will exhaust into the atmosphere while air under pressure is supplied to the right end of the cylinder.

25 Upon movement of plunger 33 to the right, the head 34 moves past exhaust port 52 and head 35 moves past opening 48 (Fig. 3), thereby allowing air to enter the left end of the cylinder through opening 51. At the same time, head 36 moves past port 53 and opens the port 50 and conduit 49 to exhaust, so that air may exhaust from the right end of the cylinder.

30 The conduit 49 for introducing air to and discharging it from the right end of the cylinder 10, as shown by Fig. 5, is connected to a cylinder 54 forming part of an economiser valve. Referring to Fig. 5, the cylinder 54 has a bore 55 provided with a port 56 in communication with the conduit 49, and a plunger 57 reciprocating in the bore and which has a reduced intermediate portion 58. The plunger is normally urged to the left by a reciprocating pin 59 engaged by a pivoted arm 60 located outside the right end of the cylinder and which is connected to one end of a spring 61 disposed in a tubular guide, which may be adjustably tensioned by a screw 62 connected to the other end of the spring. Around the port 56, the bore has a groove 63 and a similar groove 64 is provided in spaced relation and to the left of the groove 63. The grooves 63 and 64 communicate by means of passageways 65 and 66, respectively, with a conduit 67, which, as shown by Fig. 1, extends to and is connected to the right end of the cylinder 10. The passageway 65 has a spring pressed ball valve 68 for allowing air to flow through the passageway from the conduit 67, but preventing a reverse flow of the air. A conduit 69, connected to the conduit 67 and to the left end of the cylinder 54, introduces fluid under pressure from the conduit to the left end of the cylinder 54 and it may be noted that the left end of the plunger 57 has a sealing ring to prevent fluid flowing past this end of the plunger.

35 Assuming that the valves shown by Figs. 2, 3 and 5 are positioned as shown, the left side of piston 13 is open to exhaust, and air under pressure flows through conduit 49, and, as shown by Fig. 5, into port 56, and then through port 66 into conduit 67 and to the right end of the cylinder 10. As the pressure builds up in the conduit 67, it is applied through conduit 69 and against the left end of the plunger 57 and the left end of the latter moves to the right and over groove 64 and cuts off the supply. This movement occurs when the tension on spring 61 is overcome and by adjusting the screw 62 the cut off may be varied. In this manner, only a part of the line pressure is used. While the plunger 57 might repeat its reciprocatory movement, owing to lowering of the pressure in the cylinder 10 as the piston 13 moves, it can be seen that the fluid utilized in returning piston 13 to the left is reduced in pressure and amount. After the piston 20 reaches the left end of the cylinder, plunger 57 will be at the right end of cylinder 54 and will remain there. An air vent is provided at the right end of cylinder 54 to avoid any trapping of air.

40 When the plunger 33 in Figs. 2 and 3 shifts to the right, the piston 13 will move to the right, and since the conduit 49 and port 56 (Fig. 5) are then open to exhaust, air from the right side of piston 13 will exhaust. The ball valve 68 enables the air to exhaust through passageway 65 as soon as port 56 is open to exhaust and it will be understood that the ball valve will open under a very low pressure so that no appreciable air resistance to movement of the piston 13 to the right is present. As soon as port 56 is open to exhaust, the ball valve opens and the air pressure in conduit 67 drops and plunger 57 then returns to the left, so that conduit 67 may freely exhaust through the passageway 66.

45 Movement of the piston 13 to the right forces the piston rod 16 into the barrel 20 and this forces liquid in the barrel through the line 24 to the gun 8.

50 In view of the fact that certain parts on the barrel 20 are also controlled by air pressure, and that the conduit 42 is interrelated with these parts, it is necessary to first describe these parts on the barrel.

55 For the purpose of insuring that the liquid side of the system will be constantly filled at all times, a reservoir 10 is provided as best shown by Fig. 6 which is fixed to the barrel 20. In this reservoir a piston 72, having a sealing ring 73, is provided which has a tubular stem portion 74 reciprocating in a tubular cap 75 closing the lower side of the reservoir. A sealing ring 76 held by a plate 77 seals the extension 73 as it enters the cap 75. The extension 74 acts as a small piston in the cap 75 and air under pressure is adapted to be admitted to the latter through a conduit 78 which is connected, as best shown by Figs. 1 and 4, to a four-way coupling 79 that in turn is connected by a conduit 80 to the air line 44. Thus constant air pressure will urge the piston 72 upwardly although it will be noted that the force urging the piston upwardly is applied against a much smaller piston working in the cap 75. For the purpose of pulling the piston 72 downwardly when liquid is introduced into the system and reservoir, and also indicating the amount of liquid in the reservoir, a rod 81 passes freely through the cap 75 and is connected to the piston. In order to prevent the operator from pulling the piston 72 all the way downwardly so that

the reservoir would be completely filled, a pin 82, having a head 83 on its lower end, projects through the extension 74 and is threaded into the piston 72, and this pin has a sleeve 84 thereon which, in conjunction with head 83, holds a collar 85 adjacent the latter. An inverted cup 86 is slidably mounted on the lower end of the pin and sleeve 84, and the upper end of the cup is normally urged downwardly against the collar by a loaded spring 87 encircling the sleeve. A weaker and pre-loaded spring 88 is disposed in the cup 86 and seats in a smaller opening in the base of cap 75 and also engages the lower side of the collar 85. This smaller opening also provides a space for the head 83, collar 85 and sleeve 84 to move into upon downward movement of piston 72.

Assuming that no air pressure is present in the lower part of the extension 75, the operator in filling the system with liquid may readily pull the piston downwardly by means of the rod 81, but this movement downwardly is resisted when the parts become positioned, as shown in Fig. 6, as the cup 86 engages the lower end of the bore 25 in cap 75, and any further movement of the piston 72 is resisted by spring 87. This normally prevents the operator from so filling the system that the reservoir is also completely filled. If it is necessary to displace liquid into the reservoir from the system during its operation, piston 72 may still move farther downwardly during which the spring 87 will be compressed lengthwise. The spring 88 is provided so as to always maintain an upward pressure on the piston 72 and prevent the latter from moving downwardly when there is no air pressure in the extension 75 and when the cup 86 is not resting on the base of the bore in the extension 75. Otherwise, with the system at rest, and without air pressure in the extension 75, there would be a tendency for the piston to gravitate downwardly and create a partial vacuum which might cause air to be drawn in at some point in the liquid side of the system.

As shown by both Figs. 6 and 7, the reservoir communicates with a side passage 90 in turn communicating with a downwardly extending bore 91 and the latter in turn communicates with a passageway 92 effected during provision of passage 90, and which is closed at its left end as shown by Fig. 6 by a plug 93. Adjacent the bore 91, and as shown by Fig. 7, the barrel 20 has lateral projections 94 and 95 which are bored as indicated at 96 and 97 respectively. The bore 96 at its inner end has an apertured valve seat 98 adapted to be closed by a ball 99. A pin 100 slidably in a bushing 101 fitting in the outer end of the bore 96 is adapted to engage the ball and hold it on the seat 98, and the outer end of the pin has a head 102 which is slidable in a cap 103 fastened to the projection 94 by bolts 104. The head 102 is engaged by a pin portion 105 projecting from a head 106, also slidable in the cap, and which has a smaller portion 107 slidable through the end wall of the cap. For constantly urging the heads 105 and 102 so as to apply closing pressure to the ball 99, a coil spring 108 is provided around the portion 107 and between the head 106 and the end of the cap. Sealing rings 109 are provided on heads 102 and 106 to prevent air between them from escaping, and similar rings are provided on bushing 101 to prevent liquid from escaping through bore 96 and around pin 100. It may be noted that the ring 109 at the outer side of bushing 101 is held in place by a plate 110.

The barrel 20 communicates with the space be-

tween the bushing 101 and valve seat 98 by a passageway 111 shown in dotted lines in Figs. 4 and 6, so that this space is always filled with liquid. A conduit 112, connected to the cap 103 and communicating with the space between heads 102 and 106, is also connected to the four-way connection 79 for supplying air under pressure to such space.

At the opposite side of the passageway 90, a bushing 113 is tightly secured in the bore 97 and a pin 114 slidable in the bushing is adapted to engage the ball 99 and unseat it. The pin has a head 115 reciprocatory in an enlarged portion 116 of the bore 97 and the outer end of the latter is closed by a cap joint 117 having an air passage 118 communicating with the space at the outer side of the head 115. Sealing rings 119 are provided to seal against escape of liquid and air, but an air vent 120 is provided between the bushing 113 and head 115 to prevent trapping of air.

The passage 118 intersects a passage 122, which at its left end is connected to the conduit 42, while the right end of the passage is connected to a conduit 123 extending to the riveting gun 8. A metering pin 124 projects into a reduced portion 125 of passage 122 adjacent the inner end of conduit 42 so as to adjustably vary the supply of air from passage 122 to the conduit. For supplying air to the connection, a conduit 126 (Fig. 8), connected to the four-way valve 79, is connected to a third passage 127 which intersects passage 122, and an adjustable metering pin 128 projects into this third passage.

In spaced relation to the metering pins, another pin 130 slidably projects through the cap 117 and is adapted to engage the head 115. A seal 131 is provided in a recess around the inner end of this pin to prevent escape of air and the outer end of the pin opening is closed by a screw 132. By removing the screw and applying pressure to the pin, the exact instant the head 115 is moved may be noted. This is desirable in that a sequence of operation of the valve 30 and ball valve 99 is desired, and in adjustment of the metering pins to obtain this sequence, it is necessary to know when the head 115 moves.

As shown by Fig. 6, the bore 91 terminates at its upper end in a smaller opening 135 which opens to the barrel 20 and the upper end of the bore has a tubular element 136 closely fitting therein which has an annular groove 137 in its outer surface and a plurality of radial openings 138 connecting the groove to the open central part of the element. The element 136 has a small opening 139 at its upper end which joins a lower and larger opening 140 and the latter opening has a valve stem 141 reciprocatory therein which terminates at its upper end in a smaller portion 142 having a tapered edge adapted to close the lower end of the smaller opening 139. The upper end portion of the stem adjacent the openings 138 has minute vertical grooves 143 extending from a shallow annular groove 144 on the stem to the upper end of the larger portion of the stem. It may be added also that an annular groove 145 is provided in bore 91 in communication with openings 90 and 92. When the smaller end of the stem is unseated by liquid pressure in the barrel 20, the pressure then also will be applied against the upper end of the larger portion of the stem, so that a pressure lower than that required to unseat the stem will hold it open. Downward movement of the stem uncovers the radial openings 138 so that liquid will flow through opening 90 into the reservoir. The mi-

nute grooves 143 and groove 144 are provided so that if there should be any slight leakage through the valve when it is closed, the leaking liquid may flow into the reservoir instead of applying pressure against the larger end of the stem and causing the valve to open. Such grooves are too small, however, to appreciably vary the above mentioned and normal operation of the valve.

The element 136 is positively held in position 10 at the upper end of the bore 91 by a bushing 146 and collar 147 in turn engaged by a sleeve 148 threaded into the lower end of the bore. The sleeve 148 has a pin 149 therein terminating at its upper end in an annular flange 150 and a portion 151 that is adapted to engage the lower end of the stem 141 and hold the valve stem in valve closing position. The pin 149 is urged upwardly by a very strong spring 152 that abuts at its lower end a screw cap 153 adjustably threaded on 20 the lower end of sleeve 148. Similarly to the construction shown by Fig. 7, sealing rings are provided, as indicated at 154, to avoid escape of liquid or entry of air.

This valve construction provides a relief valve 25 in the event the pressure on the liquid in the barrel 20 becomes undesirably greater than that required in the riveting operation, and particularly in the event the operator maintains the trigger on the gun released after the rivet is set, 30 in which event the liquid pressure would increase.

Referring now to Figs. 9 and 10, the riveting gun comprises a cylinder casting 170 having a thickened upper portion 171 upon which a handle 172 is detachably secured by means of bolts 173. 35 It may be stated at this time that the gun normally will be used with the handle uppermost and the latter is so arranged with respect to the cylinder casting and other parts of the gun that a vertical line substantially through the center of 40 gravity of the gun will pass upwardly substantially through the center of the handle so that the operator holding the gun suspended from the handle will find the axis of the cylinder substantially horizontal. This adds to the ease with 45 which the gun may be manipulated and operated. The casting 170 includes two bores 174 and 175 separated by an integral wall 176, and a tubular piston rod 178 is journaled in a bearing 179 provided in a central opening in the wall 176 for 50 reciprocatory movement axially of the bores. The bearing terminates at its right end in a flange 180 which abuts a shoulder 181 on the wall so as to prevent movement of the bearing towards the left, and at the right of the flange 180 a sealing ring 182 of cup-shaped character is provided 55 so as to positively prevent fluid at the right side of the wall 176 from flowing along the rod 178 to the left side thereof. A piston 184 is rigidly mounted on the rod 178 within the bore 174 and 60 this piston has a sealing ring 185 at its left side and around the rod to positively prevent fluid between the piston and the wall 176 from flowing between the piston and piston rod. The outer periphery of the piston is provided with sealing rings 186 similar to those mentioned which prevent fluid from flowing between the cylinder wall and the piston periphery. At its right end, the piston rod projects through a closure head 187 held against a shoulder 188 by a ring 189 threaded 65 into the end of the cylinder, and the head 187 has a bearing 190 through which the rod projects. The inner end of this bearing is flanged similarly to the bearing 179 and a sealing ring is disposed in a recess in the head to prevent fluid from flowing 70 between the piston rod and the head.

In the bore 175 a similar piston 194 is provided but this piston has an inner bearing 195 associated therewith which may reciprocate with the piston on the piston rod 178. This bearing terminates at its right end in a flange 196 and a sealing ring 197 similar to those mentioned is mounted on the right end face of the piston for preventing fluid at the right side of the latter from flowing between the piston rod and the bearing. The left side of the piston terminates in a tubular portion 198, which may reciprocate in a flanged bearing 199 secured in an apertured head 200 that is held in the left end of the cylinder by a threaded sleeve 201. A sealing ring such as mentioned may be provided at the right side of 15 the head 200 to prevent fluid from escaping along the bearing.

At the left end of the tubular portion 198 of the piston 194, a head 203 is mounted for reciprocatory movement on the piston rod and a bearing 20 204 may be provided between it and the rod. This head has a tubular portion 205 slidable in bearing 199, abutting the portion 198 of the piston so that when the piston is moved to the left, the head 203 moves therewith. 25

The head 203 at its left end terminates in three radially offset and axially directed legs 206 spaced 120 degrees apart as best shown by Fig. 14, and these legs are axially movable in recesses 207 formed in the cylinder head 200. Between the recesses inwardly directed legs 208 are thereby formed on the head 200, as also shown by Fig. 9, and it may be noted that the circumferential length of the recesses substantially is the same as the circumferential length of the legs 208. Referring now both to Figs. 9 and 15, axially beyond the end of the legs 208, the head 200 terminates in a cylindrical portion 209 of larger diameter and this tubular projection has two slots 210 spaced 60 degrees apart and which extend to the outer end 40 thereof. An outer barrel sleeve 212 is reciprocable in the tubular portion 209 and the inner end of this sleeve at one point is provided with an outwardly directed projection 213 adapted selectively to fit in one of the openings 210. It will be 45 appreciated that the slot 210 will hold the barrel sleeve 212 against turning while permitting its reciprocatory movement and that by withdrawing the barrel, it may be re-inserted with the projection 213 disposed in the other slot 210 thereby 50 positioning the barrel sleeve in a 60 degree displaced position. Reciprocatory movement of the sleeve 212 is additionally guided and supported by a sleeve 214 (Fig. 9) threaded into the end of the sleeve 201, and it will be apparent that sleeve 55 214 will normally prevent withdrawal of the barrel sleeve 212 by abutment with the projection 213 on the latter. An inner sleeve 215 is reciprocatory in the sleeve 212 and the former, as best shown by Fig. 15, has three circumferentially 60 spaced slots 216 of the same character as the slot 207 shown by Fig. 14, and these slots receive radial projections 217 at the inner end of the sleeve 212. From this description it will be appreciated that the two sleeves may reciprocate 65 relative to one another and, with the parts arranged as shown by Fig. 9, the legs 206 on the head 203 are in engagement with the projections 217 on the sleeve 212, while the end portions of the sleeve 215 between the slots 216 are in engagement with the radial projections 208 on the head 200. 70

It will now be apparent that if piston 194 moves to the left, it will move the head 203 to the left and the engagement of the legs 206 on the latter 75

- with the projections 217 on sleeve 212 will cause the latter to move to the left. The sleeve 215 may remain stationary and in abutment with the legs 208 on the cylinder head 200 as the legs 206 and 5 217 on the head 203 and sleeve 212 may move axially in the slots 216 in the sleeve. This arrangement may be reversed by removing the sleeve 214 and withdrawing the sleeves 212 and 215 and then re-inserting them with the projection 10 213 on the outer sleeve disposed in the other of the slots 210, and the reason for this selective arrangement is to enable setting of different types of rivets as set forth in the previous applications for patent mentioned.
- 15 The outer end of the piston rod 178 has an enlarged portion reciprocatory in the inner sleeve 215 and a reduced portion 221 threaded into a tubular jaw operating member 222 that is also reciprocatory in the sleeve 215. The member 222 20 at its outer end has a conical inner periphery 223 terminating at the end of the member in a circular opening, and as best shown by Fig. 16, this conical surface has three equally spaced grooves 224 of cylindrical character with the axis of each 25 cylindrical surface substantially parallel to the conical surface. These grooves respectively receive jaws 225 having outer cylindrical surfaces seated in and movable along the grooves. From this it should be appreciated that the jaws may 30 be expanded or contracted by their movement along the grooves 224 while still obtaining full and cylindrical surface contact between the jaws and the grooves. It will be noted that the grooves are not greater than semi-circular in cross section 35 and this is advantageous in that it permits inserting the jaws through the inner end of the jaw operating member 222. If the jaws had to be inserted through the front opening at the smaller end of the conical surface 223, a larger diameter 40 of the member 222 would be required and this in turn would require larger diameters of the sleeves 212 and 215 and hence the barrel of the gun would be larger and could not be inserted in certain places for riveting.
- 45 Each of the jaws has an axial extension at its inner end as indicated at 227 that has a slot 228 therein for receiving one of three radial projections 229 on the outer end of a tubular sleeve 230, which extends entirely through the piston 50 rod in a reciprocatory manner and projects from the right end thereof. This construction enables manually pulling the jaws to the right relative to the operating member 222 by pulling the outwardly projecting end of the tubular member 230 and this may be advantageous after the riveting operation in the event the jaws are unduly wedged in the grooves 224.
- 55 For normally urging the jaws toward the left, a sleeve 231 is slideable on the sleeve 230 and is provided with an annular shoulder 232 engaging the ends of the projections 227 on the jaws. This sleeve is urged toward the left by a coil spring 233 engaging the right end of the sleeve and which is disposed in a recess 234 provided between the 60 larger portion 220 of the piston rod and the tubular element 230. Between the flange 232 on the sleeve 231 and the end of the piston rod portion 221, an annular ring 235 of rubber or the like is provided for cushioning the jaws when the rivet pin breaks and when the jaws tend to quickly 65 move to the right with respect to the operating member 222 as the result of recoil. It may be noted here that normally this will be the action obtained so that the jaws will automatically free 70 themselves from any wedging engagement with

the grooves 224 as a result of recoil force when the pin breaks, but in the event this does not occur or for any other reason it is desired to move the jaws to the right relative to the member 222, the right end of the sleeve 230 may be gripped 5 from the exterior of the gun and the sleeve pulled to move the jaws.

10 The inner surfaces of the jaws are generally cylindrical with the axis thereof substantially coinciding with the axis of the piston rod and such inner gripping surfaces are provided with grooves for gripping a grooved portion of the rivet pin. For engaging the tubular part of the rivet, the outer end of the sleeve 215 terminates in an anvil 15 237 that has a tubular projection 238, while the outer end of the sleeve 212 terminates in an anvil 239 having a slightly tapered entry opening 240.

20 The right and outer end of the sleeve 230 has a short sleeve 241 secured thereon, such as by pins or a split ring 242, and this short sleeve has an enlarged bore at its left end containing a coiled spring 243 abutting the right end of the piston rod 178. This arrangement insures movement of sleeve 230 with the piston rod 178 when the latter moves to the right, so as to hold the 25 lugs or ears 229 at the left end of the sleeve at the right end of the slots 228 in the jaws. In setting a rivet, breaking of the rivet pin causes the jaws to move to the right relative to the piston rod 178, and hence relative to sleeve 230, and if 30 the lugs 229 were not at the right end of the slots 228 in the jaws, the jaws might engage the lugs and break them off. It may be added that the length of the slots 228 to the left of lugs 229 (as shown in Fig. 9) is greater than that permissible 35 movement of the jaws relative to the piston rod and member 222 as governed by the linear space between the shoulder 232 and the left end of the piston rod portion 221, so that with the lugs 229 normally maintained at the right end of the slots 228, engagement of the lugs with the left end of the slots upon breaking of the pin ordinarily will 40 not occur.

45 The sleeve 241 enables manual pulling of the sleeve 230 so as to move the jaws backwardly relative to the jaw openings 224. This is advantageous if the jaws ever freeze in the openings, or if it is desired to expand the jaws for any reason.

50 Now referring to Figs. 11 and 12, the casting 171 at the upper side of the gun, has an opening 244 in communication with the air line 123 and this passageway in turn communicates with an opening 245 communicating with a valve passageway 246. The passageway 246 has a valve 55 247 therein provided with axially directed peripheral spaces 248 to allow air to flow therethrough, and the central portion of the valve is normally pressed against a valve seat 249 by means of a spring 250 engaging the valve and an 60 apertured bushing 251 threaded into the passageway 245. The valve seat 249 has a central opening to allow air to pass therethrough when the valve is unseated, and this opening communicates with an opening 252 communicating with the 65 atmosphere. For unseating the valve 247 a plunger 253 is reciprocable in a head 254 closing the left end of the passageway 246, and this plunger, as best shown by Fig. 9, is adapted to be moved by one end of a bell crank 255 pivoted 70 on the handle as indicated at 256. The opposite end of the bell crank is engaged by a short arm 257 rigidly connected to a trigger 258 that is pivoted as indicated at 259 on the handle. Thus, when the trigger is raised, the plunger 253 is 75

moved toward the right unseating the valve 247 and this in turn connects the conduit 123 to the atmosphere allowing air to exhaust.

Referring to Figs. 11, 12 and 13, the passage 244 is in communication with the right end of the bore 174 and the left end of bore 175 in the gun and this is effected by providing a longitudinal passageway 265, as shown by Fig. 13, extending through the casting 171 at one side 10 of the cylinder bores, and which has its ends plugged and this passageway is in communication with the bores 174 and 175 by means of ports 266 and 267. A second port 268, as shown by Figs. 12 and 13, also communicates with the 15 right end bore 174 and with the passage 244. Now, if the trigger is pulled, the conduit 123 and the passage 244 are opened to atmosphere and the space at the right side of piston 184 and the left side of piston 194 may exhaust to atmosphere. Conversely, when the trigger is released 20 and the valve 247 closes, air under pressure may flow into the space at such sides of the pistons 184 and 194.

Referring also to Figs. 11 and 12, the liquid line 24 is threaded into a bushing 276 disposed in a bore 276 in the casting 171, and this bushing is held against a seal 277 by a threaded bushing 278. The bore 276 in turn communicates with an aperture 279, communicating in turn with a 25 downwardly directed valve bore 280 extending diagonally into the wall 176 and communicating with the bore 175 by a smaller opening 281 and with the bore 174 at the left end thereof, as indicated at 282. It may be noted that the sides of 30 the wall 176 and pistons 184 and 194 are relieved so as to insure entry of liquid properly at the adjacent sides of the pistons even though the latter are at the ends of their strokes. The lower end of the bore 280 has an apertured valve seat 283 adapted to be closed by a ball 284 disposed in a sleeve 285 holding the seat in place and having its upper end enlarged and threaded into the upper end of the bore 280. A spring 286 in the sleeve presses the ball against its seat and the 35 upper end of the spring is held by a cap 287 threaded on the sleeve. At its lower end, the sleeve has one or more openings 288 so that liquid flowing upwardly through the seat 283 may pass into the bore 280 at the outside of the sleeve. 40 Thus, liquid may flow upwardly from the bore 175 and through the valve, but it cannot flow in the reverse direction, while liquid may flow either to or from bore 174 through the bore 280.

For introducing liquid under pressure to the bore 175 at the right side of piston 194, a smaller opening 290 is formed in a tubular member 291 disposed in a bore 292 and this opening is in communication with the bore 280 by means of an opening 293. The left end of the opening 290 is normally closed by a small valve element 294 integral with a stem 295 of larger diameter which may slide in the member 291, and it will be noted that around the valve element 294 the end face of the stem is of larger diameter to provide a greater 45 area for the oil to act upon once the element is unseated from the end of opening 290. The stem 295 is urged toward the right to hold the element 294 in valve closing position by a strong tensile spring 296 disposed in a tubular cap 297 threaded 50 into the bore 292, and this spring abuts the left end of the cap at one end and at its other end a flange 298 integral with a plunger 301 which engages the stem 295. It will be seen that the element 294 will not open until considerable pressure 55 is applied and that once it opens, the larger area

against which the liquid may act at the end of the stem 295 serves to hold the valve open even though the pressure should drop materially. The member 291 is held tightly in position by the cap 297 engaging a collar 302 that in turn engages a bushing 303 abutting the left end of the member. Suitable sealing rings 304 may be provided to prevent liquid from seeping between the stem, bore, bushing 303 and member 291.

When the valve stem is moved by liquid pressure, it moves past a port 305 that communicates with an annular groove 306 in the outer surface of member 291, and the latter communicates with an opening 307 extending to the cylinder bore 175. For the purpose of preventing movement 10 of the stem by a pressure lower than that required to unseat the valve element in the event any slight leakage occurs past the latter when it is in closed position, the peripheral surface of the end portion of the stem is provided with very minute 15 grooves 308 which will allow any oil seeping past the valve element 294 to flow directly into the cylinder. If some means of this character were not provided it is possible in the event of slight leakage past the valve element, that an oil pressure 20 would be slowly built up against the end face of stem sufficient to move it and open the valve before reaching a pressure that alone would be 25 sufficient to unseat the valve element.

As best shown by Fig. 9, the system may be 30 filled with oil by providing a tapered opening 310 in the casting 171 and tapered openings 311 at each side thereof communicating respectively with the two bores 174 and 175. After filling the system the opening 310 is closed by means of a 35 tapered plug 312 held tightly in place by means of a button 313 on a plate 314 that is secured by bolts 315 to the casting. For the purpose of facilitating removal of the plug 312, a screw 316 may be threaded thereinto and when screwed downwardly it may be engaged with the base of the opening 310 to dislodge the plug and force it 40 upwardly.

The system may be filled with the gun 8 uppermost by pouring liquid thereinto. Liquid flows 45 then into the conduit 24 and into the barrel 20. Air may be allowed to escape from the barrel by providing a screw plug 320 on the barrel 20 (Fig. 1) which may be removed. During filling of the system the ball 99 (Fig. 7) must be unseated to 50 allow liquid to flow into the reservoir and this may be done by having air pressure on the head 115; or the pin 130 (Fig. 8) could be moved inwardly against the head to unseat the ball. The operator pulls the piston 72 downwardly (Fig. 6) 55 by means of rod 81 until the cup 86 is seated at the base of cap 75 so as to have the reservoir filled above the piston as shown. The air pressure below piston 72 will be cut off during this manual movement of the piston and, if desired, a valve in conduit 75 may be utilized for this purpose.

Now referring to Figs. 23 and 24, the rivet may 60 comprise a tubular element 325 having an intermediate portion of smaller internal diameter, an external head 326 and a tubular portion projecting from the opposite side of the structure to be riveted and which is indicated at 327. The rivet pin, which is indicated at 328, has a break neck 329 of smaller diameter than the remainder of the pin, a series of locking grooves 330 to the left 65 of the break neck, a shoulder head 331, a larger left end portion 332, a head 333, and gripping grooves 334 at the opposite end of the pin. A spreader ring 335 is provided on the larger portion 332 of the pin and is adapted to increase in 70

size when the head 333 engages it so as to provide a larger part for bulbing the tubular portion 327 of the tubular member. When the rivet is set, the pin is pulled with the reactionary force applied against the head 326, and this causes the head 331 first to expand the larger intermediate portion of the tubular member, then the head 333 acting through the spreader ring 335 causes the tubular portion of the tubular member to bulb outwardly into a head as shown in Fig. 24, and then the head 326 is contracted radially to force metal into the locking grooves 330 which are then disposed within the head, and then further tension on the pin causes it to break at the break neck 329 then located at the outer side of the head 326. In setting the rivet, it is inserted as shown by Fig. 23 and the gun is moved into a position where the pin projects into the jaws 227 and it will be recalled that the jaws have grooves for receiving the grooves 334 on the pin. The operation of the system may now be described.

Assuming that the system is properly filled with oil and the air line connections are made, the gun is properly associated with the rivet pin and thus brought into a position in which the anvil portion 238 lies against the outer radial face of the rivet head 326. With the trigger 258 in closed position, air under pressure through supply line 44 is applied to the head 43 in the valve 30 shown by Fig. 3, and also against the larger head 39 by air through conduits 80 and 126 (Fig. 4), to the connection on the barrel 20 and passages 127 and 122 (Fig. 8), and then through conduit 42. The larger size of head 39 of course maintains the valve shown by Fig. 3 at its left position. Also air pressure is applied against head 115 (Fig. 7) and while air pressure is applied against head 102 through conduit 112 and spring 108 exerts a force against such head 102, the larger size of head 115 is sufficient to hold ball valve 99 open. Also air under pressure holds the piston 13 in the booster at its left end position.

When the trigger 258 is pulled, the line 123 is opened to exhaust and this opens all of the above mentioned conduits to exhaust. The metering pins 128 and 124 are so adjusted that air will exhaust more quickly from passageway 118 than it will from conduits 42 and 126, and this insures closing of ball valve 99 before actuation of the booster control valve 30 shown by Fig. 3, so as to avoid a condition where the ball valve would be open when the piston 13 begins to move to the right. Furthermore, the conduit 78 leading to the reservoir is open to exhaust, thereby withdrawing this active pressure in the piston. Pulling of the trigger also exhausts air from the cylinder spaces in the gun at the right side of the piston 184 and at the left side of the piston 194.

The piston 13, upon operation of the valve shown by Fig. 3, begins to move toward the right forcing the liquid in the barrel through the conduit 24 and to the gun, and, as will be evidenced from Fig. 12, this liquid flows immediately into the cylinder bore 174 and at the left side of the piston 184. This causes the piston 184 to move toward the right, carrying with it the piston rod 178 and the jaw operating member 222. Positive and forceful contraction of the jaws results in locking them strongly to the rivet pin and continued movement of the piston 184 will cause movement of the rivet pin while the reactionary force is applied through the cylinder head 200, sleeve 215 and anvil 237 to the face of the rivet head 326. The operations of expanding the tubular member intermediate its ends and for-

mation of the bulbed head from the tubular portion 327 of the rivet are then effected in order, and, after formation of this bulbed head, very strong resistance is encountered to further movement of the rivet pin and this causes the liquid pressure in the barrel and in the liquid side to increase rapidly and when this pressure reaches a predetermined amount governed by the valve spring 296, shown in Fig. 12, the valve element 294 will be forced from its seat and the stem 295 will be moved to the left until liquid may flow into the cylinder bore 175 at the right side of piston 194. Then the piston 194 begins to move to the left moving with it the outer barrel sleeve 212 and anvil 239 which forces the latter over the rivet head 326 and causes its radial contraction to force metal into grooves 330 of the pin. Upon contraction of the head 326 of the rivet, resistance to movement of either of the pistons 184 and 194 will further increase, and this will cause the liquid pressure in the system to build up to a point where the rivet pin will be so tensioned that it will break at the break neck 329. Ordinarily, when the pin breaks, the recoil force on the jaws will cause the jaws to move rearwardly and the broken part to pass rearwardly through the jaws and through the piston rod and sleeve 230 and to be ejected from the right end thereof.

If the trigger on the gun is now released, air pressure will build up in the conduit 123, 42, 126, 112 and 78, and this will cause the valve element 33 to move to the left to admit air to the right end of the booster cylinder so that the piston in the latter will return to the left end of the cylinder. Simultaneously the valve element 294 shown by Fig. 12 will close and air under pressure will build up at the right side of piston 184 and at the left side of piston 194 causing these pistons to return to their original positions thereby forcing the liquid at their opposite sides back into the barrel 20. As will be seen in Fig. 12, the liquid at the right side of piston 194 may flow out of the cylinder bore 175 through the passageway 281 and past the ball 284 as the latter will be unseated by the pressure on the liquid due to the air pressure at the opposite side of the piston. Release of the trigger causes air pressure to build up quickly below the reservoir piston 72 and at the outer sides of heads 115 and 102 in the reservoir valve (Fig. 7), and while there is liquid pressure on the outer side of ball 99, the ball will normally be unseated. It may be added that the metering pins in Figs. 7 and 8 are so adjusted that the ball 99 is unseated before valve 33 is actuated, or in any event the ball is unseated at least simultaneously with initial movement of piston 13 to the left, and this avoids a condition where the reservoir piston could not act to supply liquid to and avoid vacuum in the barrel when the piston 13 begins to so move. As soon as valve 33 in Fig. 2 is actuated by air pressure at the right side of head 38, the valve 33 shifts to the left, thus causing air to exhaust at the left side of piston 13 in the booster and air pressure to build up at the right side of the piston. This releases the great pressure on the liquid in barrel 20 as the piston rod 16 moves to the left. Now if the booster piston returns at a higher rate of speed than that at which the liquid can be returned from the gun to the barrel, so as to tend to create a vacuum in the barrel, air pressure through the conduit 78 will force the piston 72 in the reservoir upwardly to keep the

barrel filled with liquid. If the booster piston reaches its left end position and ceases to move, and the liquid from the gun has not entirely flown back, or rather, if the pistons 184 and 194 have not reached the wall 176 in the gun, liquid may continue to flow into the barrel, as excess liquid will flow into the reservoir owing to the fact that the pressure above the reservoir piston 72 will be sufficient to overcome the air pressure below the piston in the reservoir actuated by the air from conduit 78. Liquid will thus flow into the reservoir until the pistons 184 and 194 reach their original positions adjacent the wall 176 in the gun. The spring 108 in the reservoir valve is advantageous in insuring closing of the ball valve, if at any time the air pressure is cut off. Under such circumstances, if the gun were lifted much above the booster, oil would tend to drain into the barrel and if the reservoir piston and liquid level were fairly high in the reservoir, the pressure on the liquid upon raising the gun might cause some liquid to drain from the gun into the reservoir. This would tend to create a vacuum in the gun and cause suction of air thereinto if there were any point where air might enter.

In the event the operator does not release the trigger at the end of the riveting operation, the pistons 184 and 194 will, of course, engage the rigid walls at the ends of their strokes and in this event the liquid pressure will continue to build up, but, when this pressure reaches a predetermined amount, the valve element 142 and stem 141, shown by Fig. 6, will move downwardly 35 against the action of the strong spring 152, and this will allow liquid to flow into the reservoir and it will be apparent that the valve will remain open even though the pressure reduces somewhat owing to the larger size of the stem. A greater downward movement of the piston 72 in this event is provided for if necessary by compression of the spring 87, and ordinarily the system will be filled with liquid to such extent, as previously mentioned, to allow liquid to flow into the reservoir until the piston 13 and gun pistons 40 184 and 194 reach the right end of their strokes.

The system may be filled with liquid or replenished, if ever necessary, with the pistons 184 and 194 in the position shown in Fig. 9, and 45 the booster piston at the left end of the booster cylinder, by removing the plug 312 on the gun and pouring liquid into the opening. Owing to the fact that air pressure in conduit 126 maintains the ball 99 unseated, the liquid may be poured in until the gun passageways, the conduit 24, and barrel 20 are filled. Now, by manually pulling the reservoir piston 72 down, it being necessary first to cut off the air pressure line 78, the liquid may be directed into the reservoir until the latter is filled to the proper degree. It will be recalled that this manual manipulation of the reservoir piston 72 is resisted by the spring 87 if the piston is pulled downwardly more than a desired amount and this will insure 55 that the piston will still have some distance to move to allow liquid to flow therein in the event the high pressure valve on the barrel opens during or after the rivet setting operation.

Use of air pressure at opposite sides of the 60 ball valve 99 and below the reservoir piston insures a substantially uniform operation in relation to operation of valve 33 even though varying air line pressures are employed. In other words, the system is designed to operate in the same manner, even though an air line pressure

is varied, as the same proportion in forces is maintained.

Fig. 20 illustrates a different form of economizer valve arrangement in the air line connected to the right end of the cylinder 10. The parts are very similar to the construction shown by Fig. 5, excepting that the passageways 63 and 64 are connected to conduit 49 instead of conduit 77, and the port 56 opens to the latter. Also instead of using air pressure for moving the plunger 57 against the action of spring 61, it is moved by a plunger 350 projecting through the cylinder wall 11.

With the parts as shown, the piston 13 in the booster through pin 350 holds the valve plunger 15 20 57 at the left and no air can flow from conduit 49 to conduit 67. When the valve 30 is operated to exhaust air from the right side of piston 13 and to supply air to the left side of the piston, air from the right side of the piston will exhaust 25 through the ball valve 68 and when the piston 13 moves, the spring 61 will move the plunger 57 until the opening 64 also connects conduits 49 and 67. This also will cause plunger 350 to be projected into the cylinder 10. 25

Upon a reverse operation of valve 30, air will be introduced into the right end of cylinder 10 and exhausted from the left end and full line pressure will act on the left side of piston 13 until the piston moves plunger 350 and through 30 it, the plunger 57 to the position shown. Opening 64 will be closed shortly after piston 13 engages plunger 350, and then no further air will be supplied to the right end of the cylinder and the air under pressure in such end of the cylinder will continue to expand and move to the piston until it reaches the left end of its stroke. 35

Thus, the air pressure is cut off before the piston 13 reaches the left end of its stroke, thereby economizing on the air used in returning the piston. 40

Figs. 21 and 22 illustrate an improved form of jaw arrangement in the gun. Here the jaws 225 engage at their inner ends a relatively heavy metal inertia ring 354 that in turn engages a sleeve 355 having an enlarged end 356 engaging a spring 357, that in turn engages a shoulder 358 on the rod portion 221. It will be noted that this sleeve does not pass through to the other end of the piston rod 178. The spring 357 50 normally urges the inertia ring 354 and jaws 55 forwardly and with the jaws in the normally operative position shown a substantial space 359 exists between the end of rod portion 221 and the ring.

The jaws 225 are also and individually urged inwardly by springs having intermediate coiled portions 360 disposed in slots 361 in the member 222 and each coiled portion is pivotal on a pin 362 projecting through the slot. Frontwardly, the coils have ends 363 extending forwardly in recesses 364 in member 222, and which terminate in radial ends 365 projecting through small openings 366 in such member and into axial grooves 367 in the jaws, respectively. The other ends of the coils have radial ends 368 projecting into openings 369 in the jaws respectively, and by pressing against the rear walls of such openings, such ends urge the jaws individually away from the outer end of member 222. 70

When the rivet pin breaks, the large recoil force tends to throw the jaws back and relative to member 222, and it is important that the full force of this recoil not be absorbed by striking of the jaws against rod portion 221. The spring 75

358 is occasionally not enough of a cushion against such force of the recoil. The ring 355, however, interposes an inertia force and its weight is such that the rearward throw of the 5 jaws is slowed up owing to the fact that the jaws must pick up this weight and carry it with them, and while the jaws and ring both move rearwardly, the recoil force is dissipated enough that final engagement of ring 355 with the end 10 of rod portion 221 is not damaging to the jaws or ring.

The spring ends 365 and 366 do not interfere with movement of the jaws and the ends 365 particularly maintain the jaws against turning 15 or circumferential displacement. The ends 366, while normally urging the jaws rearwardly, are not strong enough to overcome spring 358 so that the latter normally maintains the jaws seated in grooves 223 in member 222. These 20 ends 366 are provided to move the jaws rearwardly and expand them when it is desired to withdraw an unset rivet gripped by the jaws, but manifestly it will be first necessary to move sleeve 355 rearwardly before the ends 366 can 25 perform this function. To move sleeve 355 rearwardly, an expanding tool 375 may be inserted from the right end of rod 178, and, while any suitable tool may be used, it is shown as comprising a tube 376 having segments 377 separated by slots 378, and a rod 379 threaded into the tube as indicated at 380, and which has a tapered head 381 for expanding the segments. When the segments are expanded into gripping 30 relation with sleeve 355 by turning rod 379 relative to tube 376, the tool may be pulled to the right so as to move the sleeve.

A modified arrangement of the system may be used as shown by Figs. 17, 18 and 19. Instead of using air under a comparatively low pressure, 40 fairly high liquid pressure may be used to operate the booster piston and in this event in order to obtain the required liquid pressure in the barrel, the booster cylinder may be of smaller size as shown. Air may be used to operate the booster 45 valve 30, reservoir valve and to supply air to the reservoir below its piston. In this construction, the air line 44 is directly connected to the base of the reservoir by a conduit 385. The passage 45 in valve 30, as shown by Fig. 19, also extends to 50 the right end of bore 32 and communicates therewith through an opening 386, the effective size of which may be varied by a metering pin 387. With air supplied against both heads 43 and 37, the plunger 33 is held in its left position. Conduits 388 and 389 are connected to the cap 41 and conduit 388 extends to the rivet gun, while conduit 388 extends to the reservoir valve (shown by Fig. 7) and is connected to the outer end of bore 37, although it may also be connected to bore 36 between heads 102 and 106 or, if desired, the spring 108 alone may be used to seat the ball valve 99. When the trigger on the gun is operated, air exhausts from conduits 388 and 389, and from the right end of bore 32 in booster valve 30, 55 and the latter valve operates to control movement of the booster piston 13 to the right. This also causes the ball 99 in the reservoir valve to become seated. No economizer valve in the conduit 61 is shown, but it may be used, and, in fact, 60 the same booster valve, economizer valve, reservoir valve, and reservoir may be employed as described previously and as shown by Figs. 1 to 8, inclusive, except that liquid is employed to move piston 13. In the construction shown, the longitudinal aperture 45 in the booster valve, shown

by Fig. 19, is not in communication with the bore 34, and a liquid inlet 390 is connected to a conduit 391 that extends to a liquid pump 392. For exhausting liquid from opposite sides of the piston in the booster, the exhaust ports 52 and 53 are connected to an exhaust line 393 that extends to the inlet side of the pump 392. With this system, the gun is operated in the same way by pulling the trigger which exhausts the larger bore portion 32 of the booster valve causing the valve 10 element 33 to move to the right and it will be readily understood from the previous description how the liquid under pressure will flow to one end or the other end of the booster cylinder depending upon the position of the valve.

Although more than one form of the invention has been illustrated and described in detail, it will be apparent to those skilled in the art that various modifications may be made without departing from the scope of the appended claims.

I claim:

1. A rivet setting apparatus comprising a closed liquid fluid pressure system including a rivet setting mechanism and a liquid fluid pressure device, movable means in the pressure device for applying pressure to the liquid in the system, movable means in the mechanism and actuated by said liquid pressure for setting a rivet, manually controlled means for effecting movement of said movable means in the pressure device to apply pressure to the liquid and for reversing movement of the movable means after the riveting operation, and means separate from the first means and controlled by operation of said manually controlled means for injecting liquid into the system at any time during reverse movement of the movable means in the event the space volume in the liquid system exceeds the liquid volume.

2. A rivet setting apparatus comprising a closed liquid system including a rivet setting mechanism and a remotely located liquid pressure boosting device, liquid fluid pressure responsive means in the riveting mechanism for setting a rivet, reciprocable means in the boosting device for forcing liquid into the mechanism and applying pressure to the liquid in the system, fluid pressure actuated means for reciprocating the reciprocable means, a reservoir for liquid on the boosting device, means including a manually operable means on the mechanism for effecting reciprocation of the reciprocable means, and means separate from the reciprocable means and automatically controlled by said manually operable means for opening said reservoir to communicate with the liquid system.

3. A rivet setting apparatus comprising a closed liquid pressure system including fluid pressure responsive riveting means and reciprocable means for forcing liquid against the responsive means to set a rivet, means including manually controlled means for effecting said reciprocable movement of the reciprocable means, a liquid reservoir, a valve separate from the reciprocable means for opening the system to the reservoir, and means controlled by the manually controlled means for opening the valve when the movement of the reciprocable means is reversed after the rivet setting operation.

4. A rivet setting apparatus comprising a rivet setting mechanism, a liquid fluid pressure boosting device comprising a cylinder and a barrel smaller than the cylinder, a piston reciprocable in the cylinder, a plunger reciprocable in the barrel and movable with the piston, means for con-

ducting liquid from the barrel into the mechanism, liquid pressure means for moving the piston, fluid pressure actuated valve means for controlling operation of said liquid pressure means, and means on the mechanism for controlling the fluid pressure actuated valve means.

5. A rivet setting apparatus comprising a rivet setting mechanism, a liquid fluid pressure boosting device comprising a cylinder and a barrel 10 smaller than the cylinder, a piston reciprocable in the cylinder, a plunger reciprocable in the barrel and movable with the piston, means for conducting liquid from the barrel into the mechanism, liquid pressure means for moving the piston, air pressure actuated valve means for controlling operation of said liquid pressure means, and means on the mechanism for controlling the air pressure actuated valve means.

6. A rivet setting apparatus comprising fluid 20 pressure responsive rivet setting means, a reciprocatory device for supplying liquid fluid under pressure to the responsive means, a liquid reservoir for supplying liquid to the system, valve means for connecting the reservoir to the system, control means for effecting reciprocation of the pressure supplying device, means for operating the control means, and means for effecting operation of the valve means previous to or at 25 least simultaneous with operation of the control means.

7. The combination in a liquid fluid pressure system, reciprocatory fluid pressure responsive means, reciprocatory fluid pressure means for supplying fluid under pressure when moving in one direction to the responsive means, a reservoir 35 for liquid, means connecting the reservoir to the system including valve means and means for

positively opening the valve prior to movement of the fluid pressure means in said other direction.

8. The combination in a liquid fluid pressure system, including pressure responsive means for performing work and reciprocatory means for supplying liquid under pressure to the responsive means, a liquid reservoir for the system, means connecting the reservoir to the system, a valve for opening and closing the reservoir to the system, additional fluid pressure means for actuating the reciprocatory means, and means actuated by the fluid pressure actuating the additional means for actuating the valve.

9. A fluid pressure device comprising fluid pressure responsive means, means for introducing fluid under pressure to one side of the responsive means to actuate the latter in one direction, means for introducing gaseous fluid under pressure to the other side of the responsive means to return the latter, and means operable automatically to cut off the supply of the gaseous fluid prior to complete return of the responsive means.

10. A fluid pressure device comprising fluid pressure responsive means, means for introducing fluid under pressure to one side of the responsive means to actuate the latter in one direction, means for introducing gaseous fluid under pressure to the other side of the responsive means to return the latter, and means operable automatically to cut off the supply of the gaseous fluid prior to complete return of the responsive means, the latter automatic means including a valve having a pin portion adapted to be engaged by a part of the responsive means prior to complete return of the latter.

LOUIS C. HUCK.
